United States Patent Office

Des. 180,760
Patented Aug. 13, 1957

180,760

KNIFE OR SIMILAR ARTICLE

Henry B. Baer, New York, N. Y., assignor to Imperial Knife Company, Inc., New York, N. Y., a corporation of Rhode Island

Application November 2, 1955, Serial No. 38,692

Term of patent 14 years

(Cl. D22—3)

Fig. 1 is a side view of a knife, showing my new design; Figs. 2, 3, 4 and 5 are top, bottom, rear and front views respectively, of said knife.

I claim:

The ornamental design for a knife or similar article, substantially as shown.
